UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A COAT.

Application filed January 16, 1926. Serial No. 16,132. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Coat, of which the following is a specification, reference being had to the accompanying drawing, forming part thereof, wherein—

The coat is distinguished by an ornamental scalloped edge on the front opening from the top to the bottom, with a lining

matching in color and general appearance with a scarf connected with the coat at the rear of the neck opening and extending downwardly to substantially the waist-line when in a tied position.

The figure is a front view of a coat partly thrown open showing my new design, the coat being illustrated on a figure.

I claim:

The ornamental design for a coat, substantially as shown and described.

TAUBE DAVIS.
